UNITED STATES PATENT OFFICE.

JOHN K. STEWART, OF CHICAGO, ILLINOIS, ASSIGNOR TO STEWART-WARNER SPEEDOMETER CORPORATION, OF CHICAGO, ILLINOIS, A CORPORATION OF VIRGINIA.

DESIGN FOR AN AIR-PUMP CASING.

45,974.

Specification for Design.

Patented June 16, 1914.

Application filed March 18, 1914. Serial No. 825,705. Term of patent 14 years.

To all whom it may concern:

Be it known that I, JOHN K. STEWART, a citizen of the United States, residing at Chicago, in the county of Cook and State of Illinois, have invented a new, original, and ornamental Design for an Air-Pump Casing, of which the following is a specification, reference being had to the accompanying drawings, forming a part thereof.

The drawing is a perspective view of an air pump casing made in accordance with my new design.

I claim:—

The ornamental design for an air pump casing, as shown.

In testimony whereof I have hereunto set my hand at Chicago, Illinois, this 11th day of March, 1914.

JOHN K. STEWART.
